AUTOMATIC CHOKE FOR GUN BARRELS

James H. Kitzmiller, Reading, Pa.

Application June 2, 1938, Serial No. 211,311

5 Claims. (Cl. 42—79)

This invention relates to shot guns, and has particular reference to means constituting an automatic choke for constricting the discharge end of the gun barrel.

When in the field or firing at a close target, the barrel of a shot gun should be opened or unchoked to give a large pattern and to prevent blowing the target to pieces. When in the field and the game normally moving away from the shooter is missed by the first shot, the automatic choke operated by the recoil of the first shot will give distance and killing power to the second shot on the game which has naturally moved farther away. It has been found in practice that it is not practicable to adjust a choke by hand. Sighting is interrupted. The game is permitted to move farther away while this adjustment is being made by hand, and various other objections to hand-adjustable choke means have been found.

The object of the present invention is to provide automatic choke means for constricting the discharge end of the gun barrel to give distance and greater concentration of the charge.

A further object of the invention is to provide in an automatic choke device, means for locking the operative parts in their open or constricted position.

A still further object of the invention is to provide such automatic choke means with mechanism for quickly attaching or removing the same from the gun barrel.

According to the invention, the automatic choke means, which may be applied either to the end of the gun barrel per se or to the end of the gun barrel in the form of an attachment, has a barrel provided with a series of longitudinal slots at the discharge end thereof, a portion at the discharge end enlarged above the normal outer diameter and tapering to the normal diameter, a sleeve having a sliding fit on the normal outer diameter of said barrel, and arranged upon the gun recoil to encompass said enlarged area to reduce the discharge diameter of said barrel. The sliding member may be provided with means for locking it in either position, and it may be provided with means for limiting its movement in either direction.

The drawing illustrates embodiments of the invention and the views therein are as follows:

Figure 1 is a side view showing the broken end of a gun barrel with the automatic choke in the form of an attachment added thereto.

Figure 2 is an end view of the same,

Figure 3 is a longitudinal sectional view taken on the line 3—3 of Figure 1.

Figure 4 is a vertical sectional view taken on the line 4—4 of Figure 3.

Figure 5 is an enlarged view showing the means for locking the choke sleeve in open or closed position, and

Figure 6 is a view similar to Figure 3, and shows the end of a gun barrel per se adapted for incorporating the invention.

As illustrated in the drawing, the shot gun barrel 11 may be externally threaded as at 12 to receive the internally threaded sleeve 13 of a gun barrel extension 14, whose normal bore 16 is identical with the bore 17 of the gun barrel. The extension 14 has a concentric shoulder 18 tapering at 19 to the normal outer diameter 21 of said extension, which said diameter may be the same as the outer diameter 22 of the gun barrel. The discharge end 23 of the extension 14 has a series of saw-cuts or slots 24 longitudinal thereof, and extending some distance back from said discharge end. These slots 24 are of sufficient width to permit the outer diameter of the shoulder 18 to be reduced to the diameter 21. The extension is provided with a peripheral slideway 26. A sleeve 27, whose inner diameter is such as to provide a sliding fit with the outer normal diameter 21 of the extension 14, fits over the same, and has a key 28 resting in a keyway 29, which said key is broken at 31 to allow the same to be sprung outward to slide over the shoulder 18, and spring into the slideway 26. This extension is provided with an enlargement 32, and, in turn, this enlargement has a hole 33 into which a tool may be placed for bearing against the ends of the spring key 28 to spread the same so as to release it from the slideway 26, when it is desired to remove the sleeve 27 from the extension.

The extension 14 may be provided with a guideway 34 for the end 36 of a pin 37. This pin may have a thumb piece 38 on its outer end and a leaf spring 39 for placing tension against the movement of said pin.

The guideway 34 may have the forward well 41 and the rear well 42 for receiving the enlarged end of the pin 37 to lock the sleeve 27 against movement from either the open or constricted position. This pin 37 is, of course, manually operable, and provides means to prevent the operation of the automatic choke when shooting at short range, or to provide a choke discharge when shooting at long range.

Figure 6 shows the movable sleeve 27 con-

nected with the end of the gun barrel per se. This view shows the sleeve in a position to constrict the end of the gun barrel. In this instance, all the parts as herein described in connection with the extension placed on the gun barrel will be found except the extension and attending parts per se, and the end of the gun barrel may be provided with the shoulder 18, tapered part 19, and longitudinal slots 24, when new guns are built to incorporate this invention.

This invention has been tested over a long period of time, and has been found to give remarkable results; the gun recoil, commonly called the "kick" or "kick back," pulling the barrel to the rear, so that the sleeve slides up the tapered portion 19 onto the shoulder 18 and automatically provides a constricted barrel for the second shot.

Of course, the automatic choke device for gun barrels herein illustrated and described may be modified in various ways without departing from the invention herein set forth and hereafter claimed.

The invention is hereby claimed as follows:

1. A gun barrel having a normally uniform bore, an external tapered enlargement at the discharge end of said barrel, said barrel having slots extending inward from the discharge end thereof, and a sleeve-like member constructed and arranged to slide freely on said barrel and to automatically ride onto said tapered enlargement in response to the recoil of the gun to thereby constrict the discharge end of said bore.

2. A gun barrel having a normally uniform bore, an external tapered enlargement at the discharge end of said barrel, said barrel having slots extending inward from the discharge end thereof, a sleeve-like member constructed and arranged to slide freely on said barrel and to automatically ride onto said tapered enlarge-

ment in response to the recoil of the gun to thereby constrict the discharge end of said bore, and means for limiting the relative movement of said member on said barrel.

3. A gun barrel having a normally uniform bore, an external tapered enlargement at the discharge end of said barrel, said barrel having slots extending inward from the discharge end thereof, a sleeve-like member constructed and arranged to slide freely on said barrel and to automatically ride onto said tapered enlargement in response to the recoil of the gun to thereby constrict the discharge end of said bore, and means for locking said member in either position.

4. An automatic choke device for guns comprising a gun barrel having a normally uniform bore and an external periphery uniform except at the discharge end of said barrel which is provided with a tapered enlargement, longitudinal slots extending from the discharge end of said barrel, and a member constructed and arranged for free sliding on the uniform periphery of said barrel and to automatically ride onto said enlargement for embracing the enlargement to restrict the outer end of the bore in response to the recoil of said gun.

5. An automatic choke device for guns comprising a gun barrel having a normally uniform bore and an external periphery uniform except at the discharge end of said barrel which is provided with a tapered enlargement, a member constructed and arranged for free sliding on the uniform periphery of said barrel and to automatically ride onto said enlargement for embracing the enlargement to restrict the outer end of the bore in response to the recoil of said gun, and means for preventing the member from leaving said barrel.

JAMES H. KITZMILLER.
